[57] **CLAIM**

The ornamental design of the a combined rectal speculum and obturator for enemas and colon hydrotherapy, as shown and described.

DESCRIPTION

FIG. 1 is a perspective view of a combined rectal speculum and obturator for enemas and colon hydrotherapy showing my new design, shown in separated condition;

FIG. 2 is a perspective view thereof, shown in assembled condition;

FIG. 3 is a bottom plan view of the rectal speculum as seem in FIG. 1;

FIG. 4 is a front view of the rectal speculum as seem in FIG. 1;

FIG. 5 is a side view of the rectal speculum as seem in FIG. 1, the opposite side view being identical thereto;

FIG. 6 is a rear view of the rectal speculum as seem in FIG. 1;

FIG. 7 is a top plan view of the rectal speculum as seem in FIG. 1;

FIG. 8 is a bottom plan view of the obturator as seem in FIG. 1;

FIG. 9 is a front view of the obturator as seem in FIG. 1, the rear view being identical thereto;

FIG. 10 is a side view of the obturator as seem in FIG. 1, the opposite side view being identical thereto; and,

FIG. 11 is a top view of the rectal speculum as seem in FIG. 1.
